MULTIPLYING MACHINE

Francis Galvin Wood, Los Angeles, Calif., assignor to Twentieth Century-Fox Film Corporation, Los Angeles, Calif., a corporation of New York

Application June 17, 1939, Serial No. 279,710

2 Claims. (Cl. 235—61.10)

This invention relates to tabulating machines employing record cards and deals particularly with a multiplying machine of the type shown in Patent Number 2,165,230, granted July 11, 1939, to J. M. Cunningham.

The invention to be hereinafter described is an addition to machines of the above character, which in practice will eliminate one or more operations required under the ordinary use. The present record card controlled machines used for multiplying are so constructed that in the field in the card where recordings are to be made the machine will record zeros until the first significant figure appears. It will be understood by those skilled in this art that the multiplying machine referred to will record a result in a pre-determined field, which field can be used to control a check writing machine and that when the card is later used to control a check writing machine the zero recordings ahead of the significant figures in this field will be ignored by the check writing machine. To print the customary asterisks or stars ahead of the significant figures on the check, the usual practice is to sort the cards according to the number of zeros appearing before the significant figures and to then rerun the cards through another machine set up to cause recordings above the regular field corresponding to the number of zeros ahead of the first significant figure, said recordings being positioned to operate magnets on the check writing machine that cause the machine to print asterisks or equivalent signs.

Under my invention a change over device is incorporated in the multiplying machine that will change over the connection from the read out to the zero magnet, so that the zero magnet will not respond to the read out but an auxiliary magnet in the multiplying machine will be energized instead. The auxiliary magnet referred to is one of the extra magnets incorporated in a multiplying machine as standard equipment and is arranged to cause recordings above the regular field in the card. Normally it is not used in the regular machine operation. After the change over has been made the auxiliary magnet will be operated by the zero connection to the read out until a positive number is reached in the read out, whereupon the change over will switch the connection back to the zero magnet and zeros will be properly recorded for the remainder of the field in the card. The result is a series of recordings above the regular field in the card, said recordings corresponding to the number of zeros before the first significant figure appearing in the result to be recorded in the field. The field mentioned is later used to control a check writing machine and the series of recordings above this field will operate magnets in the check writing machine that print asterisks or equivalent

signs on a check. The device may be installed upon a standard multiplying machine and operated without affecting any other parts or operations of the machine except those specifically mentioned. The recordings mentioned herein are the conventional holes punched in record cards by a plurality of punch magnets under control of the read-out lines.

In the drawing I have shown a simplified illustration of how my invention may be applied to a conventional multiplying machine of the type shown in the above mentioned patent. Figure 1 is a wiring diagram showing the selector magnets with my change over device incorporated therein; Figure 2 shows a fragmentary part of the multiplying machine in conjunction with an auxiliary circuit for operating the change over device shown in Figure 1; and Figure 3 shows a conventional payroll card.

10 Briefly stated, my invention consists of an automatic change over device between the zero magnet and an auxiliary magnet whereby the read out circuit normally connected to the zero magnet may be switched over to operate the auxiliary magnet. In the drawing I have shown a series of selector magnets designated 0 to 9 inclusive, and 11 and 12. These magnets correspond to the magnets designated 120 in Patent Number 2,126,595 granted August 9, 1938, to H. Weinlich et al. In Figure 2, I have generally designated these same magnets 120. With respect to the magnets, it is to be understood that the ordinary multiplying machine carries twelve magnets, ten of which are used to punch holes corresponding to numerals, and two of which, namely 11 and 12, are usually not employed in the ordinary multiplying operation. In my invention I utilize one of the magnets, either 11 or 12, in this instance magnet 12, for my purpose, and whenever the magnet 12 is mentioned herein it is to be understood that this term is intended to include any magnet that causes a recording in the card above the regular field. Referring again to Figure 1, it will be noted that one side of the magnets, 0 to 9, inclusive, are connected to conductors 0' to 9' respectively, which lead to their respective connections on the read out device and correspond to wires 52 (Fig. 1b of the Cunningham patent mentioned above). Since this invention is concerned solely with an addition which affects only two of the magnets, and since the operation of the invention is not dependent upon nor is connected with any other electrical operation of the machine, the description will not include operations of other parts of the machine but will be confined to that part only which is affected. The read out device mentioned herein corresponds to the conventional circuits illustrated in Fig. 1b of the same Cunningham patent. It will be noted, with respect to Figure 1, that the lower

side of the magnets 1 to 9, inclusive, are connected to a line 13 and that the lower side of the magnets 0 and 12 are connected to a line 14. Both lines 13 and 14 are connected to line 54, which corresponds to line 54 of Cunningham. In the line 13, I incorporate a relay coil B.

Referring to Figure 2, it will be observed that I have shown fragmentarily a machine embodying the aforementioned selector magnets 120 and a card carrier rack 74 which corresponds to the card carrier rack 74, shown in Fig. 16, of the Weinlich patent. In conjunction with the card carrier rack, I incorporate a circuit comprising switch S, key K, relay coil A, contact points 1A, contact points 1B, and key L. The circuit is connected to the same source of supply through line 54 and line 55. It will be noted that key K is paralleled across the contacts 1A, the purpose of which will become apparent presently. It will also be observed that the coil B is paralleled by contacts 3A and that double contacts 2A are arranged in the line 0' connecting the 0 magnet to the read out device so that the control of the read out device may be switched from the 0 magnet to the 12 magnet and vice versa. On the card carrier rack 74, I mount a fixture M, which in this instance is shown as a form of an extending arm that is adapted to engage and close the key K as the rack travels a predetermined distance, which distance is determined by the field on the card that controls the check writing machine. The key L is also arranged to be engaged and opened after the rack travels a predetermined distance beyond the closing of the key K.

In operation, a record card having items punched in different columns, such as is illustrated in Figure 3, is fed into the multiplying machine by means of the rack 74, and the machine calculates the various items and as the card travels records a result in the check writing field designated 15. In recording the result in the check writing field, the multiplying machine under the ordinary set-up will record zeros until the first significant figure is reached, whereupon it records the actual amount carried over into the field. According to my invention, as the card carrier rack 74 carries the card C into the machine, the arm M will engage and close the key K as the check writing field 15 enters the recording position in the machine. Assuming that the switch S is closed, the coil A will become energized and will close the contact points 1A, thus forming a circuit independent of the key K, which by virtue of the travel of the carrier rack 74 is only momentarily closed. At the same time coil A operates contacts 2A, which disconnects the 0 magnet and places the 12 magnet under control of the read out. Also, contacts 3A are opened, thus throwing coil B in series with line 13. According to this circuit, any impulse from the read out normally transmitted to the 0 magnet will be transmitted to the 12 magnet instead. As explained hereinbefore, the 12 magnet is arranged to cause recordings in the card above the regular field, which recordings are subsequently used to operate magnets in a check writing machine that prints asterisks or equivalent signs on a check. This arrangement will hold until any one of the other magnets from 1 to 9 are energized, which will in turn energize the coil B and break the contacts 1B, thus de-energizing the coil A and allowing the contacts 2A to swing back and connect the zero magnet to its proper read out connection. At the same

time the contact points 3A will close and shunt out the coil B and the magnets 0 to 9 inclusive will then operate in the conventional way. As the rack continues to travel, it will encounter 5 and open the switch L, thus breaking the auxiliary circuit independently of the key K and the contacts 1A. It is to be understood that the switch L is a precautionary switch and is placed in the circuit merely to insure that the circuit 10 will be opened at the end of the card travel in case no significant figures appear in the check writing field. The result, as shown on the card C, is a series of recordings 16 in the upper portion of the card above the regular control field, 15 said recordings being arranged to control punch magnets in a check writing machine which, as before stated, have been adapted to print the desired signs such as asterisks or stars.

The above described operation whereby zero 20 recordings in the check writing field are converted into other recordings outside the regular field to control magnets in a check writing machine for the purpose described is automatically performed in the multiplying machine, thus eliminating sorting and rerecording of the cards before use in the check writing machine.

The means employed for the purpose is simple, inexpensive, and may be incorporated in a conventional multiplying machine with minor 30 alterations.

I claim:

1. In a multiplying machine having a plurality of magnets for causing recording on a card, said magnets including a zero magnet for causing recording of zeros in a field on said card, a series of read-out lines normally connected to said magnets for controlling the same, an auxiliary magnet normally not connected to said read-out lines for causing recordings on said card 35 above said field, a movable card carrier for carrying a card into a recording position in said machine, a relay for transferring a read-out line from said zero magnet to said auxiliary magnet, means for energizing said relay as a predetermined field on said card enters the recording position in said machine, a second relay common to all other of said magnets operable upon energization of any of said other magnets to de-energize 40 said first mentioned relay and transfer the read-out line from said auxiliary magnet to said zero magnet.

2. In a multiplying machine having a plurality of magnets for causing recording on a card, said magnets including a zero magnet for causing recording of zeros in a field on said card, a series of read-out lines normally connected to said magnets for controlling the same, an auxiliary magnet normally not connected to said read-out 45 lines for causing recordings on said card above said field, a movable card carrier for carrying a card into a recording position in said machine, a relay for transferring a read-out line from said zero magnet to said auxiliary magnet, switch means operable by the movement of said card carrier for energizing said relay as a preselected field on said card enters the recording position of said machine, and a second relay arranged to be operated by the energization of any other 50 of said magnets for de-energizing said first mentioned relay to transfer said read-out control from said auxiliary magnet to said zero magnet when any other of said plurality of magnets is operated.
